UNITED STATES PATENT OFFICE.

CLARENCE G. CASHMAN, OF WAYNESBORO, PENNSYLVANIA.

REAMER-HEAD.

1,332,802.

Specification of Letters Patent.

Patented Mar. 2, 1920.

Application filed January 13, 1917. Serial No. 142,275.

To all whom it may concern:

Be it known that I, CLARENCE G. CASHMAN, a citizen of the United States, residing at Waynesboro, Franklin county, and State of Pennsylvania, have invented and discovered certain new and useful Improvements in Reamer-Heads, of which the following is a specification.

My said invention relates to cutter or reamer heads and consists in the combinations and arrangements of elements herein-after described and particularly set forth in the accompanying claims.

The purpose of the invention is to provide a cutter or reamer head of the radial adjustable blade type, wherein the blades are locked in set position; having means for simultaneously adjusting the several blades by a simple and easily performed operation; and wherein the adjusting device consists of few parts that may be readily assembled or disassembled.

The invention has for its further purpose to provide a blade adjusting device for such a tool in which the blade engaging member and locking device therefor are concealed wholly within the reamer head, thereby having the reamer exterior free from obstructing parts.

The invention is shown by way of illustration in the accompanying drawing, wherein:

Figure 1 is a central longitudinal section through a reamer head, constructed in accordance with my said invention,

Fig. 2 is a transverse sectional view thereof taken on the line 2—2 of Fig. 1,

Fig. 3 is a similar view taken on the line 3—3,

Fig. 4 is a detail view, partly in section of the body of the reamer head, and

Fig. 5 is a perspective view of one of the reamer blades.

Referring to the construction in further detail, and wherein like reference characters designate corresponding parts, 6 represents the machine spindle on which the reamer head is mounted, 7 the body of said reamer head and 8 the several blades, which may be formed as shown or as required to adapt them for any character or cutting or reaming for which the tool may be intended.

The head consists of a cylinder constructed for mounting on the machine mandrel and is provided with a plurality of longi-

tudinal grooves, or seats 9, arranged equidistant apart around its periphery, and adapted to receive and hold the blades. Said seats or grooves are formed with their bottom surfaces inclined downward from the rear to front, and the reamer blades are formed with complementary tapered inner edges 10. Each of the grooves 9 has an inset portion 11 along a portion of its inner surface to receive the longitudinal rib 12 formed on the lower edge of the blade to hold said blade against radial displacement.

The blade adjusting device consists of a screw-threaded member 13 adjustably mounted in a threaded aperture formed centrally in the body 7 and constructed at its outer end with a socket 14, rectangular in cross-section, by which a tool or wrench (not shown) may be inserted for turning the same to adjust the several blades.

A disk 15 of relatively large diameter, is mounted on the reduced portion 16 of the screw bolt 13 and engages within notches 17 formed on the respective inner and lower edges of the several blades 8 after the manner shown in Fig. 1. A nut 18 screw-threaded on the inner end of the member 16 secures said disk against axial displacement and a locking device is provided for holding the disk against angular movement.

The locking device comprises a pin or screw 17^a screw-threaded on the disk 15 and engaging within a recess 19 formed in the inner face of the central body portion 7. Said pin 17^a thereby locks the disk 15 against angular movement relative to the body 7, and securely holds the several blades 8 in set position. The locking disk 15 is constructed with a plurality of peripheral notches 20 disposed equidistant and adapted to be brought into register with the several notches 17 of the blades when said blades are then free to be moved longitudinally.

The blade securing device is wholly concealed within the body of the reamer head and is therefore accessible only through the rear of the head, or after the reamer is removed from the machine spindle. The locking pin 17^a is formed with a notch 21 to receive a screw driver or like instrument when the disk is to be turned for connection with the blades or disconnection therefrom, as will be understood.

It is obvious that the details of construction and arrangement of parts may be modified in various particulars without departing

from the spirit of my invention, and therefore I do not wish to be limited to such features except as may be required by the claims.

5 Having thus fully described my said invention, what I claim as new and desire to secure by Letters Patent, is:—

10 1. A tool comprising a body formed with radially disposed grooves, blades mounted to have radial adjustment in said grooves, means for imparting radial adjustment to said blades, and a blade locking pin engaging with the blade adjusting member and located wholly within said body, substantially as set forth.

15 2. A tool comprising a body formed with radially disposed grooves, blades mounted to have radial adjustment in said grooves, a device for imparting radial adjustment to the blades, and a pin carried by the adjusting device for locking the said device to the body to secure the blades in set position, substantially as set forth.

20 3. A tool comprising a body formed with radially disposed grooves, blades mounted to have radial adjustment in said grooves, an adjustable member mounted in the body, a member mounted on said adjustable member and engaging with the blades to impart adjustment thereto, and a member carried by the blade engaging member adapted to engage with said body to secure said blade engaging member from rotation, substantially as set forth.

25 4. A tool comprising a body formed with radially disposed grooves, blades mounted to have radial adjustment in said grooves, an adjustable member mounted in the body, a disk mounted on said adjustable member engaging with the blades to impart longitudinal adjustment thereto, and a pin mounted on said disk adapted to engage with said body and provide a lock to secure the disk in set angular position, substantially set forth.

30 45 5. A tool comprising a body formed with radially disposed grooves, blades mounted to have radial adjustment in said grooves,

a member having screw adjustment in said body, a disk mounted to have angular movement on the adjustable member and engaging with said blades when in one position to impart adjustment thereto and adapted to be freed from such engagement when turned to another position; and a pin adjustably mounted on said disk adapted to engage with the body to hold said disk in set position, substantially as set forth. 50 55

6. A tool comprising a body formed with radially disposed grooves, blades mounted to have radial adjustment in said grooves and constructed with notched edges, a screw-threaded member adjustably mounted centrally in said body, a notched disk mounted to have angular movement on said adjustable member engaging with the notches of said blades to secure the latter in set position; a pin screw-threaded on said disk adapted to engage with said body to hold said disk in set position, and the notches of 60 65 said disk adapted when said disk is turned to register with the notches of the blades to allow of longitudinal movement of said blades, substantially as set forth. 70

7. A tool comprising a body having a recess and formed with radially disposed grooves, blades slidably mounted in said grooves, said blades and grooves having complementary inclined portions to effect the radial adjustment of the blades; a screw-threaded member mounted centrally of the body, a disk mounted on said member within said recess and engaging with the blades to impart adjustment thereto, and a member carried by said disk adapted for engaging with the body to guide and hold the disk in set position, substantially as set forth. 75 80 85

In witness whereof I have hereunto set my hand and seal at Waynesboro, Pennsylvania, this 5th day of January, A. D. nineteen hundred and seventeen. 90

CLARENCE G. CASHMAN. [L. S.]
